UNITED STATES PATENT OFFICE.

HAROLD L. WHEELER, OF BUFFALO, NEW YORK.

DESIGN FOR A CUP.

SPECIFICATION forming part of Design No. 34,918, dated August 13, 1901.

Application filed June 6, 1901. Serial No. 63,480. Term of patent 7 years.

To all whom it may concern:

Be it known that I, HAROLD L. WHEELER, a citizen of the United States, residing at Buffalo, in the county of Erie and State of New York, have invented and produced a new and original Design for a Cup, of which the following is a specification, reference being had to the accompanying drawing, which represents a perspective view of a cup embodying my design.

The design comprises a cup presenting the base *a* and stem *b*, above which latter appear the twin cup-sections *c*, said cup-sections being joined by a curved and fluted connecting member *d*, poised on the stem *b*.

The leading feature of the design resides in the twin cup-sections *c*.

Having described my invention, what I claim as new, and desire to secure by Letters Patent, is—

The design for a cup, as herein shown and described.

In testimony whereof I have signed my name to this specification in the presence of two subscribing witnesses.

HAROLD L. WHEELER.
